FIGURE 1 is a top plan view of one form of compartmented packaging tray embodying my new design;

FIGURE 2 is a side elevational view of the tray of FIGURE 1;

FIGURE 3 is a fragmentary longitudinal sectional view taken on the line 3-3 of FIGURE 1 and on a larger scale;

FIGURE 4 is a fragmentary longitudinal sectional view taken on the line 4-4 of FIGURE 1 and on the same scale as FIGURE 3;

FIGURE 5 is a fragmentary transverse sectional view taken on the line 5-5 of FIGURE 2;

FIGURE 6 is a fragmentary perspective view of the tray of FIGURES 1 to 5;

FIGURE 7 is a top plan view of another form of compartmented packaging tray embodying my new design;

FIGURE 8 is a side elevational view of the tray of FIGURE 7;

FIGURE 9 is a fragmentary longitudinal sectional view taken on the line 9-9 of FIGURE 7;

FIGURE 10 is a fragmentary longitudinal sectional view taken on the line 10-10 of FIGURE 7;

FIGURE 11 is a fragmentary transverse sectional view taken on the line 11-11 of FIGURE 8; and

FIGURE 12 is a fragmentary perspective view of the tray of FIGURES 7 to 11.

My new design is characterized by a series of narrow lateral grooves and a longitudinal central row of closely spaced lateral elongated projections, the portions of the tray between adjacent projections being rounded in cross section and projecting downwardly from the bottom surface of the tray, all as shown.

I claim:

The ornamental design for a compartmented packaging tray, as shown and described.
